United States Patent Office

Des. 187,462
Patented Mar. 22, 1960

187,462

FROST, ICE, AND SNOW SCRAPER

Frank S. Elliott, Jr., Creve Coeur, Mo., assignor to Skinner, & Kennedy Company, St. Louis, Mo., a corporation of Missouri

Application October 2, 1959, Serial No. 57,771

Term of patent 14 years

(Cl. D9—6)

FIG.1

FIG.2

FIG.3

FIG.4

FIG.5

Fig. 1 is a top plan view of a frost, ice and snow scraper showing my new design,

Fig. 2 is a right side elevational view thereof, the left side not shown being substantially the same,

Fig. 3 is a front elevational view thereof,

Fig. 4 is a rear elevational view thereof, and

Fig. 5 is a bottom plan view thereof.

I claim:

The ornamental design for a frost, ice, and snow scraper, substantially as shown and described.
